ROTARY CLASSIFIER FOR PULVERIZERS
AND THE LIKE

Ralph M. Hardgrove, Westfield, N. J., assignor to
The Babcock & Wilcox Company, Newark, N. J.,
a corporation of New Jersey

Application December 20, 1934, Serial No. 758,385

9 Claims. (Cl. 83—45)

My present invention relates in general to the construction of rotary classifiers and more particularly to rotary classifiers adapted for use in material pulverizers in which the pulverized material is removed by a gaseous carrier medium.

A main object of my invention is the provision of an improved construction of a rotary classifier which is characterized by its simple and low cost construction, effective operation, low pressure loss, and avoidance of material deposits therein. A further object is the provision of improved driving means for a rotary classifier incorporated in a pulverizer which are characterized by the substantial elimination of vibratory stresses therein, the use therewith of effective classifier sealing provisions, and the elimination of gearing.

The various features of novelty which characterize my invention are pointed out with particularity in the claims annexed to and forming a part of this specification. For a better understanding of the invention, its operating advantages and specific objects attained by its use, reference should be had to the accompanying drawings and descriptive matter in which I have illustrated and described a preferred embodiment of my invention.

Of the drawings:

Fig. 1 is a sectional elevation of a pulverizer incorporating my invention;

Fig. 2 is an enlarged view of the rotary classifier shown in Fig. 1; and

Fig. 3 is a section on the line 3—3 of Fig. 2.

In the drawings, I have illustrated a pulverizer incorporating a rotary classifier constructed and arranged in accordance with my invention. As shown, the pulverizer has a vertically arranged sectional casing 10 of circular cross-section mounted on a suitable foundation 11 and enclosing a plurality of relatively movable grinding parts which cooperate to form a plurality of material grinding stages. The grinding parts include a non-rotary floating upper grinding ring 12, a rotary floating intermediate grinding ring 13, and a stationary lower grinding ring 14, between which are positioned upper and lower circular rows of grinding balls 15.

Rotation of the intermediate grinding ring and contacting rows of balls is effected by a drive shaft 16 arranged axially of the rows of balls and held in vertical alignment by an upper roller bearing 17 and a bottom thrust bearing 18. At its upper end the drive shaft carries a drive yoke 20 having one or more plates 21 on its outer side positioned between corresponding pairs of plates 22 on the inner side of the intermediate ring and

providing a floating drive connection for the intermediate ring. A suitable grinding pressure is superposed on the grinding parts by a series of coiled springs 19 acting on the upper ring 12. At the lower end of the casing 10 is formed an annular box 23 having an inlet 24 thereto for the delivery of any suitable gaseous carrier medium, such as preheated air. The air box 23 is connected by radial passages 25 to the inner side of the lower row of balls. Transverse ports 26 are arranged in the intermediate ring for the outward passage of material-laden air. A pipe 27 is connected to the casing 10 above the grinding parts for the delivery of the material to be pulverized onto a conical plate 28 at the inner side of the upper row of balls. With the foregoing construction and arrangement of the grinding parts, the material passes outwardly through the upper row of balls and then inwardly through the lower row, and a stream of air is passed upwardly to the casing, sweeping up material from the inner side of the lower row of balls before passing outwardly through the ports 26 and then upwardly past the outer side of the upper row of balls.

In the pulverizer shown, the top wall 29 of the casing is formed with a symmetrically arranged group of outlets 30 for the material-laden air. Each of the outlets is provided with a swingable externally operated valve disc 31 for regulating the delivery of pulverized material.

The material in suspension in the ascending air stream includes a substantial amount of oversize or coarse particles. Various types of classifying devices have heretofore been used in the upper section of the pulverizer for separating oversize material from the air stream before it leaves the pulverizer and returning the coarse material separated to the grinding section. In the present construction, a classifier of the rotary type is arranged in the upper part of the pulverizer casing in the path of the material-laden air stream to the the casing outlets 30. As shown in Figs. 2 and 3, the classifier is formed by a horizontally arranged substantially conical bottom plate 33 flaring downwardly for a distance outside the area occupied by the group of outlets 30, so that the air stream will be forced to pass outwardly around the plate 33. The plate 33 has an inclination of about 27° to the horizontal, while the extreme outer portion 33a of the plate preferably has a greater inclination, as shown. An annular top plate 34 is arranged in vertical alignment with the section 33a of the bottom plate and provided with a vertical flange 34a extending upwardly at

its inner side. The flange 34^a fits rotatably within the reduced lower end of a circular seal plate 35 extending downwardly from the casing top wall 29 and surrounding the outlets 30 so that short circuiting of the classifier is prevented by the effective seal so provided. The seal plate 35 forms in effect a common extension for the outlets 30. Between and connected to the top plate 34 and the bottom plate section 33^a is arranged a series of vertically extending blades 36. The blades 36 are arranged in vertical planes at similar acute angles to the circumferences of the plates 33 and 34, and with the trailing edge of the blades in vertical alignment with the circumference of the plate 33.

With the classifier described in operation, the substantially radial entry of all portions of the material-laden air into the classifier insures that a constant centrifugal force will be exerted on all of the particles of material in the entering air stream opposing their entry. As the centrifugal effect on and the momentum of the suspended particles will be proportional to the mass of the particles, the velocity of the air stream can be suitably controlled so that the centrifugal effect will prevent particles of less than the desired degree of fineness from entering the interior of the classifier. A definite separation or classification of the suspended material can be thereby effected. Rotation of the classifier is advantageously secured in accordance with my invention by securing the plate 33 to a split clamp 41 on a vertically arranged drive shaft 40. The shaft 40 is connected to form a rigid extension of the drive shaft 16, and is secured in vertical alignment through a clutch plate 42 fastened to the top of the drive yoke 20. The lower end of the shaft 40 has a transverse recess 43 receiving a correspondingly shaped ridge 44 on the plate 42. A dowel pin 45 holds the engaging portions in position. The upper end of the shaft 40 extends through the top wall of the casing and is positioned within a roller bearing 46 mounted thereon. The form of connection of the classifier drive shaft to the pulverizer drive shaft and the mounting of the two drive shafts insures a classifier drive which is substantially free from vibratory stresses, as would occur, for example, if the shaft 40 were connected to the rotary intermediate ring.

In the operation of the pulverizer described, a substantially annular stream of material-laden air will ascend at a predetermined velocity in the casing 10 towards the outlets 30. The air stream will be directed towards the sides of the casing by the arrangement of the rotating plate 33. The pressure differential through the pulverizer will cause the stream of air to move inwardly through the passages between the moving blades 36, during which movement the suspended particles of material will be subjected to the centrifugal effect of the classifier. The centrifugal action will cause the oversize particles to be thrown outwardly toward the sides of the casing and to drop to the lower or grinding section of the casing. The centrifugal effect however, on the particles of desired fineness is not sufficient to cause those particles to be thrown out, and they remain in suspension, passing inwardly through the interblade passages to the interior of the classifier. Some of the material tends to separate within the classifier and deposit on the bottom plate 33. The conical shape of that plate however, causes any deposited material to flow downwardly into the bladed section from which

it is thrown outwardly. A useless load on the drive shafts and clogging of the interblade passages is thereby avoided. The shape of the bottom and top plates is also advantageous in producing an air flow through the classifier with a minimum pressure loss.

While in accordance with the provisions of the statutes I have illustrated and described herein the best form of my invention known to me, those skilled in the art will understand that changes may be made in the form of the apparatus and character of the carrier medium disclosed without departing from the spirit of the invention covered by my claims, and that certain features of my invention may sometimes be used without a corresponding use of other features. In my claims, the word "air" is used generically to cover any gaseous carrier medium suitable for removing pulverized material in the manner described.

I claim:

1. A pulverizer comprising a casing having an outlet for material-laden air in the top thereof, relatively movable grinding parts within said casing and cooperating to form a grinding stage, a vertically arranged drive shaft for effecting relative movement of said grinding parts and having an upper portion adjacent said outlet, means for passing a stream of air upwardly in said casing towards said outlet sweeping up pulverized material from said grinding stage during its passage, and a rotary material classifier in the path of the material-laden air adjacent to said outlet having a horizontally arranged conical plate mounted on said drive shaft and extending outwardly beyond and below said outlet, and a series of arcuately spaced blades mounted on the upper side of said plate beyond said outlet and having passages therebetween communicating with said outlet.

2. A pulverizer comprising a substantially circular casing having an outlet for material-laden air in the top thereof, relatively movable grinding parts within said casing and cooperating to form a grinding stage, a vertically arranged drive shaft for effecting relative movement of said grinding parts and having an upper portion adjacent said outlet, means for passing a stream of air upwardly in said casing towards said outlet sweeping up pulverized material from said grinding stage during its passage, and a rotary material classifier in the path of the material-laden air adjacent to said outlet having a horizontally arranged conical plate mounted on said drive shaft and extending outwardly beyond and below said outlet, and a series of arcuately spaced blades vertically mounted on the upper side of said plate outwardly beyond said outlet at an angle to the circumference thereof and having passages therebetween communicating with said outlet.

3. A pulverizer comprising a substantially circular casing having an outlet for material-laden air in the top thereof, relatively movable grinding parts within said casing and cooperating to form a grinding stage, a vertically arranged drive shaft for effecting relative movement of said grinding parts, bearing means for holding said drive shaft in vertical alignment, a vertical shaft forming an extension of and directly connected to said drive shaft and having its upper end adjacent said outlet, a bearing arranged to receive the upper end of said drive shaft extension, means for passing a stream of air upwardly in said casing towards said outlet sweeping up pul-

verized material from said grinding stage during its passage, and a rotary material classifier in the path of the material-laden air adjacent to said outlet having a horizontally arranged imperforate conical plate mounted on said drive shaft and extending outwardly beyond and below said outlet, and a series of arcuately spaced blades vertically mounted on said plate outwardly beyond said outlet at an angle to the circumference thereof and having passages therebetween communicating with said outlet.

4. In combination, a substantially circular casing having an outlet for material-laden air in the top thereof, and a rotary material classifier in said casing in the path of the material-laden air adjacent to said outlet having a vertically arranged drive shaft, a horizontally arranged imperforate conical plate mounted on said drive shaft and extending outwardly beyond and below said outlet, and a series of arcuately spaced vertically extending blades mounted on the upper side of said plate outwardly beyond said outlet at an oblique angle to the circumference of said plate and having passageways therebetween communicating with said outlet.

5. A pulverizer comprising a casing having an outlet for material-laden air in the upper part thereof, upper and lower horizontally arranged grinding rings within said casing, a circular row of rolling grinding elements positioned between said rings and cooperating therewith to form a grinding stage, a vertically fixed drive shaft having a floating drive connection with said upper ring, drive means operatively connected with the lower end of said drive shaft, means for directing a stream of air upwardly in said casing towards said outlet and sweeping up pulverized material from said grinding stage during its passage, a rotary material classifier in the path of the material-laden air having a horizontally arranged substantially imperforate plate mounted on said drive shaft and extending outwardly below said outlet, a series of arcuately spaced blades vertically mounted on the upper side of said plate and having passages therebetween communicating with said outlet, and sealing means for preventing the passage of material-laden air to said outlet other than inwardly through said classifier interblade passages.

6. A pulverizer comprising a casing having an outlet for material-laden air in the upper part thereof, upper and lower horizontally arranged grinding rings within said casing, a circular row of rolling grinding elements positioned between said rings and cooperating therewith to form a grinding stage, a vertically fixed drive shaft having a floating drive connection with said upper ring, drive means operatively connected with the lower end of said drive shaft, a vertical shaft forming an extension of and operatively connected to said drive shaft and having its upper end adjacent said outlet, means for directing a stream of air upwardly in said casing towards said outlet and sweeping up pulverized material from said grinding stage during its passage, a rotary material classifier in the path of the material-laden air having a horizontally arranged substantially imperforate plate mounted on said drive shaft extension and extending outwardly below said outlet, and a series of arcuately spaced

blades vertically mounted on the upper side of said plate and having passages therebetween communicating with said outlet.

7. A pulverizer comprising a casing having an outlet for material-laden air in the upper part thereof, upper and lower horizontally arranged grinding rings within said casing, a circular row of rolling grinding elements positioned between said rings and cooperating therewith to form a grinding stage, a vertically fixed drive shaft having a floating drive connection with said upper ring, drive means operatively connected with the lower end of said drive shaft, a vertical shaft forming an extension of and directly connected to said drive shaft and having its upper end adjacent said outlet, a bearing arranged to receive the upper end of said drive shaft extension, means for directing a stream of air upwardly in said casing towards said outlet and sweeping up pulverized material from said grinding stage during its passage, a rotary material classifier in the path of the material-laden air having a horizontally arranged substantially imperforate plate mounted on said drive shaft extension and extending outwardly below said outlet, a series of arcuately spaced blades vertically mounted on the upper side of said plate and having passages therebetween communicating with said outlet, and sealing means for preventing the passage of material-laden air to said outlet other than inwardly through said classifier interblade passages.

8. In combination, a casing having a plurality of outlets for material-laden air in the top thereof, a seal plate surrounding said outlets and forming a common extension thereof within said casing, and a rotary material classifier in said casing in the path of the material-laden air adjacent to said outlets having a drive shaft, a substantially imperforate conical plate mounted on said drive shaft and extending below said seal plate, and a series of arcuately spaced blades mounted on the upper side of said plate and having passageways therebetween communicating with said outlets, said classifier and seal plate being so relatively arranged as to require all of the material-laden air passing to said outlets to flow inwardly through said classifier interblade passages.

9. In combination, a casing having an outlet for material-laden air in the upper part thereof, and a rotary material classifier in said casing in the path of the material-laden air adjacent to said outlet having a vertically arranged drive shaft, a horizontally arranged substantially imperforate conical plate mounted on said drive shaft and extending outwardly beyond and below said outlet, a series of arcuately spaced vertically extending blades mounted on the upper side of said plate outwardly beyond said outlet and having passageways therebetween communicating with said outlet, the annular portion of said plate carrying said blades having a greater outward slope than the inner portion thereof, and said classifier and outlet being so relatively arranged as to require all of the material-laden air passing to said outlet to flow inwardly through said classifier interblade passages.
